UNITED STATES PATENT OFFICE.

ODILON FEHER, OF MONTREAL, CANADA.

NUT-LOCK.

SPECIFICATION forming part of Letters Patent No. 716,018, dated December 16, 1902.
Application filed October 11, 1902. Serial No. 126,874. (No model.)

To all whom it may concern:

Be it known that I, ODILON FEHER, a citizen of the French Republic, residing at Montreal, district of Montreal, Province of Quebec, Canada, have invented certain new and useful Improvements in Nut-Locks; and I do hereby declare that the following is a full, clear, and exact description of the invention, such as will enable others skilled in the art to 10 which it appertains to make and use the same.

My invention relates to an improved nut-lock for locking the track-bolts of a railway track; and it consists in the construction and 15 combination of parts hereinafter described, and more particularly pointed out in the claims.

In the drawings accompanying this specification, Figure 1 is a side elevation of a rail-joint provided with my improved nut-lock. Fig. 2 is a transverse section of the same on the line 2 2 of Fig. 1. Fig. 3 is a plan section through the center of a bolt, taken on the line 3 3 of Fig. 1. Figs. 4 and 5 are detail perspective views from the rear and front side, 25 respectively, of the socket-piece forming a part of my improved nut-lock; and Fig. 6 is a similar view of the key.

The same numerals of reference denote like parts in all the figures of the drawings.

In the drawings, 7 and 8 designate the abutting ends of two rails, 9 a pair of joint-plates, 10 a track-bolt, and 11 the nut thereof, all of these being of the usual or any preferred pattern.

The parts of my nut-lock are two in number, (designated, respectively, 12 and 13,) the first of which is shown in perspective rear and front views in Figs. 4 and 5 and the second in Fig. 6. These two parts constitute the socket and key of the nut, as will be observed. The part 12 is in the form of a square plate 14, having a central hexagonal aperture 15, adapted to fit the sides of the nut 11, and 45 preferably, also, a hexagonal sleeve 16, adapted to fit over the nut and of the same width thereof, so that its end strikes against the side of the joint-plate 9. The lower edge 17 of the plate 13 strikes against the lower flange 50 of the joint-plate or the base of the rail, so as to prevent this plate from turning. On its

front side the plate 14 carries a pair of overhanging lug-pieces 18, riveted thereto by rivets 19 and having projecting concave flanges 20, adapted to fit close around the bolt, while 55 permitting it to pass through the same freely. These flanges 20 are sufficiently offset from the plate 14 to permit the passage between them and the plate 14 of the key 13, which has a pair of legs 21, adapted to straddle the 60 threaded portion of the bolt 10, and these are preferably brought down to an edge 22 on their inner face, so as to catch in the threads of the bolt.

In setting the nut-lock in place after the 65 nut is screwed up the socket-piece 12 is simply inserted over the nut in the manner shown in Figs. 2 and 3, and the key 13 is then inserted between the flanges 20 and the plate 14 and hammered down by the application of a 70 hammer on its head 23, which will effectively lock the nut against turning and prevent the nut-lock from being accidentally removed.

Changes within the scope of the following claims may be made in the form and construction of the parts without departing from the spirit of my invention, and I desire it to be understood, therefore, that I reserve the right to make such modifications in the form and dimensions as will be apparent to those skilled 75 in the art.

Having thus described my invention, what I claim as new, and desire to secure by Letters Patent, is—

1. A nut-lock comprising a socket-piece 85 having a polygonal socket adapted to fit the nut and a projecting plate 14 adapted to strike against the base of the rail or joint-plate to prevent said socket from turning, a recess in said socket adapted to receive a key, and a 90 key adapted to straddle said bolt and to be driven into said recess to lock the socket-piece in place, substantially as described.

2. A nut-lock comprising a socket-piece having a polygonal recess adapted to receive 95 a nut and prevent it from turning therein, means for preventing said socket-piece from turning relative to the rail, a pair of lug-pieces secured on one face of said socket-piece and having flanges slightly offset from said socket-piece, whereby to receive a key, and a key 100 adapted to be driven between said flanges

and socket-piece and to straddle the bolt and to interlock with the threads thereof, substantially as described.

3. A nut-lock comprising a socket-piece having a polygonal sleeve 16 and a plate 14 having an edge 17 adapted to strike against the base of the rail or joint-plate to prevent said socket-piece from turning, a pair of lug-pieces secured to the front face of said socket-piece and having overhanging flanges 20 embracing the end of the bolt, and a two-legged

key adapted to straddle the bolt and having the interior edges of its legs sharpened, whereby to strike between the threads of said bolt and hold said socket-piece against coming off, substantially as described.

In witness whereof I have hereunto set my hand in the presence of two witnesses.

ODILON FEHER.
